[57] **CLAIM**

The ornamental design for a communication terminal, as shown and described.

DESCRIPTION

FIG. 1 is a top view of a communication terminal showing my new design, with the keyboard in an extended operating position, and with a telephone handpiece in broken lines for illustrative purposes only, not forming a part of the claimed design;

FIG. 2 is a perspective view from the right side of the communication terminal of FIG. 1;

FIG. 3 is a front view of the communication terminal of FIG. 1;

FIG. 4 is a perspective view of the left side of the communication terminal of FIG. 1;

FIG. 5 is a back elevational view of the communication terminal of FIG. 1;

FIG. 6 is a bottom plan view of the communication terminal keyboard in a retracted, stored position; and,

FIG. 7 is a top view of the communication terminal of FIG. 1, with the keyboard in a retracted and stored position, and with a telephone handpiece in broken lines for illustrative purposes only, not forming a part of the claimed design.
